DESIGN FOR A PUMPKIN LANTERN

Bernard Wilmsen, Philadelphia, Pa.

Application November 22, 1934, Serial No. 54,121

Term of patent 14 years

To all whom it may concern:

Be it known, that I, Bernard Wilmsen, a citizen of the United States, and a resident of Philadelphia, in the county of Philadelphia and State of Pennsylvania, have invented a new, original, and ornamental Design for a Pumpkin Lantern, of which the following is a specification, reference being had to the accompanying drawing, forming part hereof in which:

Fig. 1 represents a front elevation of a pumpkin lantern embodying my invention.

Fig. 2 represents a side elevation of Fig. 1 with the cap removed.

Fig. 3 represents a top plan view of Fig. 1.

I claim:

The ornamental design for a pumpkin lantern substantially as shown.

In testimony whereof, I affix my signature.

BERNARD WILMSEN.
